SHEET METAL PUNCHING APPARATUS

Frederick H. Johnson, Detroit, Mich.

Application April 30, 1937, Serial No. 140,026

2 Claims. (Cl. 164—95)

My invention relates to a hydraulic sheet metal punching apparatus for producing simultaneously, a large number of holes in sheet metal, such as rivet holes, or for punching out or punching up parts of sheet metal for any desired purpose.

The invention particularly provides a hydraulic stripper device carried by a hydraulically operated plunger and operative to withdraw the punch and the plunger from the work and means for alternately connecting the hydraulic actuated parts with a source of supply of fluid under pressure. The invention eliminates the high resistant springs commonly used for withdrawing punches from the work and thus reduces the hydraulic pressure required to punch the work and at the same time, compress the springs.

The invention may be contained in structures of different forms and to illustrate a practical application of the invention, I have selected an apparatus containing the invention, as an example of the structures embodying the invention, and shall describe the selected structure herein-after. The particular apparatus selected is shown in the accompanying drawings.

Fig. 1 illustrates a part of the apparatus where in a plurality of sheet metal punching devices are used for hydraulically forming a plurality of holes in sheet metal bent to a desired shape. Fig. 2 illustrates a view of a section of one of the devices shown in Fig. 1.

In the particular form of apparatus shown in the drawings, the punching devices are supported on a suitable bed or frame 1 and disposed at desired angles relative to each other according to the configuration of the sheet metal and the location of the points at which the holes are to be formed in the metal. The punching devices are individually supported on frames or brackets 2 that may be bolted to the bed or frame 1. The frame 1 or brackets 2, or both, may be shaped into different forms according to the lines of holes to be formed and the angular relation of the parts in which the holes are to be formed by the different punches and enable the operation of the punches in directions at right angles to the surface of the metal. The sheet metal is located in position such that it may be pressed against a support or die or anvil during the punching operation. The support or frame or die is shaped to conform to the line along which the openings are to be formed in the sheet metal by the punches. In the form of construction shown, a plurality of anvils 4, in the form of brackets, are disposed in position to engage the metal at points opposite the points of engage-

ment of the punches. The anvils 4 are arranged in conformance to the line of holes to be formed in the sheet metal and in positions to support the metal while it is being punched. The anvils 4 are secured by bolts to the bed or frame 1 in opposing relation to the brackets 2 that support the punching devices.

The punching devices 5 are provided with cylinders 7 and pistons 8. The cylinders 7 are secured in the brackets 2. A plunger 10 is connected to each piston 8. The plunger 10 may be in the form of a crosshead connected to the outer end of the piston 8. Also, each punching device 5 is provided with a pair of cylinders 12 and pistons 14. The cylinders 12 are secured to the ends of the plunger 10 and are carried with the plunger as it is reciprocated. The cylinders extend through the brackets 2 and are slidably supported therein and operate to guide the plunger as it is reciprocated. A pressure member 15 is connected to the pistons 14 and is moved against the work by the pistons 8 to engage and hold the work during the punching operation. The pistons 8 and 14 are operated by fluid pressures in the cylinders 7 and 12. The flow of the fluid to the cylinder is controlled by a valve that may be operated by any suitable means for connecting the cylinders to a source of supply of fluid under pressure.

A valve 18 is suitably mounted with reference to the punching devices and is provided with a manually operable handle 20 for alternately connecting the cylinders 7 and 12 with a source of supply of fluid which is conducted to the valve through a pipe 21 and from the valve through a pipe 22. The valve is connected by flexible pipes 23 to the cylinders 7 and by flexible pipes 24 to the cylinders 12 and is operable to cause simultaneous operation of, first, all of the pistons 8 and then all of the pistons 14.

Punches 16 are connected to the plungers 10. Any number of punches may be connected to each plunger. The punches extend into openings 19 formed in the pressure members 15. The work 25 is disposed intermediate the anvils 4 and the pressure members 15. When the pistons 8 are operated they first move the pressure members 15 against the work to securely hold the work and then subsequently cause the punches to form openings in the work. The valve 18 is then operated to disconnect the cylinders 7 from the source and to connect the cylinders 12 with the source. The pistons 14 operate to press the pressure members 15 with a greater pressure to draw the punches from the work and thereby strip the

work from the punches. The pistons 14 move the plungers 10 in a direction opposite to that in which they were moved by the operation of the pistons 8 until the punches have been pulled from the work, whereupon, the pressure members 15 and the plungers 10 are further moved from the work by the operation of suitable springs that engage the pistons 8.

The pistons 8 have suitable heads 28 located in bushings 27 for guiding the outer ends of the pistons and springs 28 are located intermediate the pistons 8 and the inner ends of the bushings 25. The springs 28 have merely a pressure sufficient to move the plungers 10, when the punches are released from the work, to remove the pressure members 15 away from the work and afford sufficient space between the pressure members and the anvils to place a succeeding piece of work in position to be punched by the succeeding simultaneous operation of the punching devices.

The cylinders 12 are provided with the cylinder heads 29 and 30. The pistons 14 extend through the heads 29. The outer ends of the pistons 14 are threaded and are adjustably connected to the pressure members 15. They may be adjustably secured relative to the pressure members 15 by the lock nuts 31. The cylinders 12 are provided with springs 32 located intermediate the heads 30 and the pistons 14. If desired, the pistons 14 may be provided with rods 35 having heads 37 that engage the pistons 14. The springs 32 surround the rods 35 and operate to maintain the pressure members 15 at a limited distance from the plungers 10 and so as to locate the pressure members 15 against the work in advance of the engagement of the work by the punches. As the punches 16 are further moved against and through the work, the springs 32, located in the cylinders 12, are compressed and press the pressure members 15 against the work.

I claim:

1. In a punching device, a punching cylinder, a punching piston located in the punching cylinder and having a piston rod extending through one end of the punching cylinder, a spring for

spring pressing the punching piston towards the other end of the punching cylinder, a member and a punch holder connected to the outer end of the piston rod, a pair of stripping cylinders carried on the member, stripping pistons located in the stripping cylinders, each of the stripping pistons having a piston rod extending through one end of its associated stripping cylinder, springs for spring pressing the stripping pistons toward the said ends of the stripping cylinders, a work engaging member connected to the ends of the piston rods of the stripping pistons, a punch connected to the punch holder, a die coacting with the punch to punch the work and means for directing fluid under pressure to the punching cylinder and the stripping cylinders to punch and strip the work from the punch.

2. In a punching apparatus, a plurality of punching devices each punching device comprising a punching cylinder, a punching piston located in the punching cylinder and having a piston rod extending through one end of the punching cylinder, a spring for spring pressing the punching piston towards the other end of the punching cylinder, a member and a punch holder connected to the outer end of the piston rod, a pair of stripping cylinders carried on the member, stripping pistons located in the stripping cylinders, each of the stripping pistons having a piston rod extending through one end of the associated stripping cylinder, springs for spring pressing the stripping pistons toward the said ends of the stripping cylinders, a work engaging member connected to the ends of the piston rods of the stripping pistons, a punch connected to the punch holder, a die coacting with the punch to punch the work, a frame having parts for supporting the punching devices at desired angles relative to each other according to the contour and relative location of the portions of the work and means for directing fluid under pressure to each of the punching cylinders and to the stripping cylinders to punch and strip the work from the punches.

FREDERICK H. JOHNSON. 45
